SAVERIO MINUNNO, OF NEW YORK, N. Y.

HAND FAN.

Application filed December 3, 1926. Serial No. 152,454.

This invention relates to a hand fan provided with a suitable motor for operating the fan blades and preferably the device is of the small type so that it can be readily carried in the pocket for convenient access.

One of the objects of the invention is to provide a hand fan with a spring motor which may be conveniently wound up from time to time and then the spring released so as to rotate the fan blades when a person desires to cool off. Another object is to provide a hand fan of the type just mentioned with a longitudinal movable handle which may be shoved inwardly in order to wind up the motor and which may be slid outwardly when it is desired to permit the motor to rotate the fan blades.

Other objects of the invention are to provide a convenient motor operated pocket fan which is of simple construction so that its cost for a device of this kind is reduced to a minimum, which may be readily operated from time to time, as desired, by a rotation of the handle whereby the entire device may be supported in one hand, and which is preferably constructed of metal so as to render it durable and to enable it to be made attractive by the use of different shapes and designs.

These being among the various objects of the present invention, the same consists of certain features of construction and combinations of parts to be hereinafter described and then claimed with reference to the accompanying drawings illustrating one embodiment of the invention, in which:

Fig. 1 is a front elevation of the fan showing it in using position;

Fig. 2 is a rear elevation, partly in section, showing the fan blades folded together;

Fig. 3 is a side elevation of the fan with the blade folded;

Fig. 4 is a longitudinal section of the fan on the line 4—4 (Fig. 6), to show the gear train;

Fig. 5 is a section on the line 5—5 (Fig. 6), to illustrate the motor spring and its relative position in the device, and

Fig. 6 is a longitudinal section viewed edgewise of the fan on the line 6—6 (Fig. 4).

Referring to the drawings, the supporting frame for the various parts of the fan comprises a casing 10 which is provided with

an opening at the back through which the various parts of the motor may be introduced into the casing. The casing 10 may be of any desired shape and may be ornamented and may be attractive in any desired manner. A mounting plate 11 is provided for supporting the elements of the gear train of the motor and also the coiled winding spring 12. This winding spring which is adapted to operate the gear train is preferably one which requires repeated winding for temporary operation of the motor, although it is obvious that the winding spring and associated parts may be made for a longer period of rotation of the fan blades, and that even in some aspects of the present invention a different type of motor may be employed which may be released from time to time to exert the desired power.

Mounted upon the plate 11 are shafts 13, 14, 15 and 16 of the gear train, the shaft 13 constituting the driving shaft from the winding spring and the shaft 16 constituting the outwardly extending driven shaft. These parts now being described are more clearly shown in Figures 4, 5 and 6.

The primary gear 17 is fixed on the driving shaft 13, while secondary gears 18, 19 are respectively fixed on shafts 14, 15. A bevel pinion 20 is fixed on the driving shaft 13, while pinions 21, 22, 23 are respectively fixed on shafts 14, 15, 16, the said gears 17, 18, 19 and the pinions 21, 22 and 23 being meshed in well known manner for transmitting the desired power from the driving shaft 13 to the ultimately driven shaft 16.

The winding and operating spring 12 is secured at its outer end to a pin 24 supported from the mounting plate 11, and the inner end of said spring is secured to the driving shaft 13, so that this type of power means for the motor may be wound up from time to time by the shaft 13 and then released to expand and exert its spring power.

Also fixed on winding shaft 13 is a ratchet wheel 25 having beveled teeth which are engaged one at a time by a pawl or dog 26 which is pivoted to the large gear 17 and which is impelled to engage the ratchet teeth by means of a bowed spring 27 which is held fast at one end on said gear 17 and at its free end is connected with the pawl 26. The function of this pawl and ratchet device in spring motors is well known.

The manner of assembling the plate 11 and

the gear train of the motor with and into the casing 10 will be readily understood by those skilled in spring motors. The shaft 13 turns in a bearing in the mounting plate 11, while the shafts 14, 15 and 16 are stepped in bearings in said plate. The shaft 16 and its pinion 23 are first mounted in the bearing of the front of the casing, and then the shafts, gears and winding spring 10 mounted on the plate 11 are passed through the rear opening of the casing 10 and the shafts 13, 14, 15 finally caused to engage the step bearings of the front of the casing. Of course the parts may be assembled in other ways.

The mounting plate 11 is preferable rigidly secured in the casing 10 in the following manner. Plate 11 is provided with an outwardly turned flange 28 which frictionally 20 engages with the inner wall of the casing, and against the edge of said flange there is placed a back plate 29 which constitutes the back of the casing. When the back plate 29 has been introduced, the rear edge of the 25 casing 10 is upset over the back plate 29 in the form of a flange 30. The flange 30 will thus hold the interior parts of the casing 10 in place. Other means may of course be adopted for securing the mounting plate 11 30 within the casing.

Inasmuch as the hand fan of the present invention is preferably of pocket size, the fan blades 31, 32 fixed on the driven shaft 16 projecting from the casing, are of such size 35 that they may be adapted for being folded in order to more readily go into one's pocket. Preferably to this end the fan blade 31 is composed of two sections connected by a hinge 33, so that the outer section may be 40 folded against the fan blade 32. It will be seen that the spring motor is of such type that the fan blades may take the position shown in Figures 2 and 3 so that the entire fan device may be readily slipped into the 45 pocket of the one who wishes to make use of the fan. It is preferred to make use of extremely convenient and simple means for winding up from time to time the spring of the preferred motor which has been 50 described.

To this end the casing 10 is provided with an opening 34 which is located adjacent the driving shaft 13 and around said opening there extends outwardly from the edge of the 55 casing a guide sleeve 35. This sleeve extends at right angles to the winding shaft 13. A handle 36 is provided which is at least of a length so as to be conveniently grasped by the hand of the user, and this 60 handle is preferably tubular, as shown in section in Fig. 2 and into its inner extremity there is rigidly fixed a plug 37. There is a stem 38 rigidly secured in the plug 37 so that its axis and the axis of the handle are 65 coincident, and upon the inner end of the

stem 38 there is fixed a winding bevel pinion 39. Pinion 39 is adapted for engagement with bevel pinion 20 on the winding shaft 13. The handle 36 is provided with a reduced end portion 40 joined with the main body of the handle by an annular shoulder 41. The reduced portion 40 snugly yet loosely fits into the guide sleeve 35 so as to locate the pinion 39 in juxtaposition to the bevel pinion 20.

Preferably the handle 36 is slidable with respect to the guide sleeve 35, into which it telescopes, and the reduced portion 40 is provided with an annular groove 42, as shown clearly in Figs. 2, 4 and 6. The opposite

side walls 43, 44 of groove 42 provide annular abutment shoulders, and between them there projects a stop pin 45 which is rigidly fixed to the guide sleeve 35. The abutment shoulders 43 and 44 and the stop pin 45 constitute means for limiting the extent of inward and outward sliding movement of the handle 36. When the handle is pushed in, the winding pinion 39 is brought in mesh with the bevel pinion 20, thereby to permit of the winding up of the spring 12 when the handle 36 is rotated. It will be seen that the annular groove 42 permits of the rotation of the handle when it is in its inward position.

When the handle 36 is pulled outwardly, the pinion 39 is unmeshed from pinion 20 and the coiled spring 12 is released, thereby operating the gear train of the motor and rapidly rotating the fan blades 31, 32 at an increased speed over the large 100 gear 17. Thus when the pinion 39 is released, the user, still grasping the handle 36, may grasp not only the handle but the sleeve 35 so as to hold the casing 10 stationary and the user may then take the benefit of the 105 breeze which is caused by the fans 31 and 32.

Preferably the parts of the described device are made up of metal, the casing and its parts and the handle and fan blades being of sheet metal, although it is obvious that 110 various features of the device may be made of other material. As viewed from the outside the device is of extreme simplicity and lends itself to any desirable design, configuration and ornamentation and may be 115 readily cleaned by the user by means of a pocket handkerchief. When in pocket size, as is preferred, the device is extremely compact and is very efficient for the desired cooling off purposes. It is obvious that the 120 described and illustrated device is capable of more or less modification without departing from the spirit of the invention as expressed by the scope of the appended claims.

What I claim as my invention, is:

1. In a hand fan, the combination of a frame, a motor mounted thereon, a fan driven by the driven shaft of the motor, a pair of meshed bevel pinions, one of which is connected with the drive shaft of the 130

motor, a stem on which the other pinion is fixed, a guide on the frame, and a longitudinally movable and rotatable handle guided by said guide and on which said other pinion is fixed.

2. In a hand fan, the combination of a frame, a motor mounted thereon, a fan driven by the driven shaft of the motor, a pair of meshed bevel pinions, one of which is connected with the drive shaft of the motor, a stem on which the other pinion is fixed, a tubular guide on the frame, and a longitudinally movable and rotatable handle guided in said guide and on the inner end 15 of which said other pinion is fixed.

3. In a hand fan, the combination of a frame, a motor mechanism mounted thereon and having a winding spring connected with the driving shaft of the same, a fan driven by the driven shaft of the motor, a bevel pinion fixed on driving shaft, a winding bevel pinion meshing with said pinion, a stem on which the winding pinion is fixed, a tubular guide on the frame and a longitudinally movable and rotatable handle telescoping with said guide, and on which the winding pinion is fixed.

4. In a hand fan, the combination of a frame, a motor mechanism mounted thereon and having a winding spring connected with the driving shaft of the same, a fan driven by the driven shaft of the motor, a bevel pinion fixed on driving shaft, a winding bevel pinion meshing with said pinion, a stem on which the winding pinion is fixed, a tubular guide on the frame, a longitudinally movable and rotatable handle telescoping with said guide, and on which the winding pinion is fixed, and a pin and 40 groove connection between the handle and guide whereby the pinions are permitted to be meshed and unmeshed.

5. In a hand fan, the combination of a frame, a motor mechanism mounted thereon and having a winding spring connected with the driving shaft of the same, a fan driven by the driven shaft of the motor, a bevel pinion fixed on driving shaft, a winding bevel pinion meshing with said pinion, a stem on which the winding pinion is fixed, a tubular guide on the frame, a longitudinally movable and rotatable handle telescoping with said guide, and on which the winding pinion is fixed, and a pin and 55 groove connection between the handle and guide whereby the pinions are permitted to be meshed and unmeshed, the pin being on the guide and the groove being in the handle, and the pin and the side walls of the groove

constituting respectively a stop and limiting 60 abutments.

6. In a hand fan, the combination of an enclosing casing constituting a supporting frame, a coiled spring therein fixed at one end to the casing, a train of speed-up gears 65 mounted on shafts in the casing, a fan mounted on the last driven of said shafts and at the outside of the casing, said spring being fixed at its other end to the main driving shaft of said gears, a bevel pinion fixed on the driving shaft, a tubular guide sleeve extending from the casing at a point adjacent the main driving shaft, a rotatable handle slidable in the guide sleeve, a stem fixed on the handle and extending into the 70 casing, a winding pinion fixed on the stem and meshing with aforesaid pinion, and means for limiting the sliding movements of the handle.

7. In a hand fan, the combination of an enclosing casing constituting a supporting frame, a coiled spring therein fixed at one end to the casing, a train of reducing gears mounted on shafts in the casing, a fan 75 mounted on the last driven of said shafts and at the outside of the casing, said spring being fixed at its other end to the main driving shaft of said gears, a bevel pinion fixed on the driving shaft, a tubular guide sleeve 80 extending from the casing at a point adjacent the main driving shaft, a rotatable handle slidable in the guide sleeve, a stem fixed on the handle and extending into the casing, a winding pinion fixed on the stem and meshing with aforesaid pinion, the 85 handle having an annular groove, and the guide sleeve having a pin entering said groove for holding the handle in place and limiting its sliding movements while permitting its rotation.

8. In a hand fan, the combination of a frame, a spring motor mounted thereon, a fan driven by the driven shaft of the motor and located laterally of the frame to face forwardly, a pair of meshed, toothed winding gears, one of which directly winds the motor, a stem for turning the other gear, a rotatable handle on which said stem is fixed with their axes in substantial alignment, and a bearing on the frame for supporting the 100 handle and stem, said handle being substantially, axially, elongated in a downward direction with respect to the frame sufficiently to be grasped by one hand of the user for winding the motor, and the fan thus positioned to deliver air currents in a direction laterally of the frame.

SAVERIO MINUNNO.
